UNITED STATES PATENT OFFICE.

CHESTER A. SIEGEL, OF NEWARK, NEW JERSEY.

LOCOMOTIVE-FIREBOX.

1,335,399.

Specification of Letters Patent. Patented Mar. 30, 1920.

Application filed December 4, 1918. Serial No. 265,206.

To all whom it may concern:

Be it known that I, CHESTER A. SIEGEL, a citizen of the United States, residing at 41 Roseville avenue, Newark, county of 5 Essex, and State of New Jersey, have invented certain new and useful Improvements in Locomotive-Fireboxes, fully described and represented in the following specification and the accompanying drawings, forming a part of the same.

This invention relates to an improvement in the bridge-wall or so-called "arch" sometimes employed in the firebox of a locomotive or tubular boiler to retard the movement 15 of the flaming gases into the tubes, and to thus retain the heated gases more effectively in contact with the crown-sheet of the firebox, to promote an increased generation of steam and better circulation of 20 water in the water legs.

In the present construction the arch may be termed a "water-arch", as it is constructed of two metal walls with the water circulated between them and connected to the 25 water-legs of the firebox and to the crown of the same.

This water-arch is extended from the grate level upwardly and backwardly so as to lean over the fuel burning upon the grate 30 and thus absorb the heat most effectively therefrom.

The ends of the arch are in communication with the water-legs, and the inclined top-portion of the arch is connected with 35 the crown of the firebox by two water-tubes which divide the space over the arch into three passages, one at the middle and the others at the sides of the firebox.

Such connections afford a free entrance 40 for the water to the water-arch and the escape of the steam therefrom into the steam-space S of the boiler.

The base of the water-arch extends to the bottom of the water-legs, and as the ends 45 of the water-arch are in open communication with the water-legs this construction permits and induces a current of the colder water from the water-legs into the bottom of the arch. The water as it is heated flows 50 upwardly by degrees into the upper part of the boiler above the crown-sheet. The circulation of water between these points is most important and advantageous.

The base of the arch is located far enough 55 from the ends of the fire-tubes to form a mixing or combustion-chamber back of the

arch in which the combustion is developed before the gases enter the tubes.

The construction will be understood by reference to the annexed drawing, in which 60 Figure 1 is a longitudinal central section of a locomotive firebox and a part of the attached barrel which contains the fire-tubes; Fig. 2 is a cross section through the water-tubes in the top of the arch on line 2—2 65 in Fig. 1; and Fig. 3 is a plan of the arch and the combustion-chamber behind the same.

A designates the water-legs of the firebox, and B the crown-sheet thereof. C is one of 70 the fuel-doors, and D the barrel of the boiler through which the fire-tubes E are extended.

The level of the grate in the bottom of the fire-box is indicated by the dotted line 75 F, and the water-arch G is extended rearwardly from the lowest point of the water-leg upward over the front end of the grate, and is curved rearwardly to lean over the rear end of the grate about one-third of the 80 grate's length.

The foot of the water-arch is connected to the side water-legs of the firebox at a considerable distance in the rear of the tube-sheet so as to form a combustion-chamber 85 J, and the arch itself is thus located in the central portion of the firebox where the heat is the greatest.

This leaves a large part of the space 90 above the grate uncovered so that the radiant heat can pass from the fuel directly to the crown-sheet, and thus heat the water above such sheet most effectively.

The projection of radiant heat from the fuel is the most effective result of the combustion, and the water-arch as just stated is so proportioned that it forms no obstruction between the fuel upon a large portion 95 of the grate, and the crown-sheet where the steam is most effectively generated.

The radiant heat from the forward part 100 of the grate acts directly upon the water in the water-arch and generates steam therein effectively; and the water-arch is thus enabled to retard the rapid passage of the gases from the firebox as desired, and to hold them somewhat longer in contact with the crown-sheet, without interfering with the effective operation of the fire upon the water above the firebox.

The front and rear plates of the water-arch are integral with one another at the

top end G', and are connected at the bottom by a spacing-piece G².

Two water-tubes H extend from the top of the arch to the crown-sheet B, being located nearer to the sides than to the middle line of the boiler, thus forming three passages I and I' from the rear part of the firebox to the combustion-chamber J in the front of the same. The water-tubes are in open connection at the bottom-ends with the water in the water-arch, and at the upper end with the water above the crown-sheet.

The ends of the water-arch are, as shown in Fig. 2, in open communication with the water in the water-legs A, and the colder water in the boiler is thus constantly flowing downward into the water-arch and upwardly through the tubes H, carrying with it any steam generated in the arch.

Such colder water of the boiler is often found in the bottom of the water-legs, and owing to the connection of the water-arch with the water-legs at their lowest point, the cold water at such point flows readily into the water-arch and rises upwardly therein as it is heated.

The firebox is extended in the front of the grate sufficiently to form the combustion-chamber J between the water-tubes H, the arch G, and the adjacent ends of the fire-tubes E.

I am aware that water connections have been extended between the side-walls of the firebox but at points considerably above the bottom of the water-legs at which point a movement of the water is most desirable to prevent the accumulation of scale. I do not therefore claim a water-arch broadly, but the particular construction and relation of my water-arch to the water-legs.

Hand-holes having removable covers M are shown at the bottom of the water-legs

in Figs. 1, 2 and 3, to facilitate the cleaning out of the bottom of the arch in case any sediment accumulates therein, and a vent L is provided in the bottom of the combustion-chamber J to remove any ashes or sediment therefrom.

My water-arch is constructed with very few parts, and this attachment for locomotive boilers is therefore cheap and durable, and may be readily applied to such boilers as are already in use. It promotes the proper mixing and combustion of the gases while retaining the operation of the radiant heat upon the crown-sheet.

My invention is thus practicable and efficient in every respect.

Having thus set forth the nature of the invention what is claimed herein is:

A locomotive boiler having a firebox with water-legs at opposite sides, a fuel-door at one end and the tube-sheet at the opposite end extending downward to the bottoms of the water-legs, a water-arch extending from the lowest point of the water-legs at the front end of the grate upwardly and rearwardly over the front end of the grate and being in open communication with the water-legs to the bottoms of said legs and producing a current of water outwardly from the bottoms of the water-legs, hand-holes and covers at the bottoms of the water-legs communicating with the lower part of the water-arch for cleaning out the same, and at least one water-tube extended from the top of the water-arch to the crown-sheet, whereby the water flows through the water-arch from the bottoms of the water-legs to the upper water-space over the firebox.

In testimony whereof I have hereunto set my hand.

CHESTER A. SIEGEL.
